UNITED STATES PATENT OFFICE

127,978

DESIGN FOR A GAME BOARD

Erich J. P. Sturm, Danville, Calif.

Application February 8, 1941, Serial No. 93,851

Term of patent 14 years

To all whom it may concern:

Be it known that I, Erich J. P. Sturm, a citizen of the United States, residing at Danville, in the county of Contra Costa, State of California, have invented a new, original, and ornamental Design for a Game Board, of which the following is a specification, reference being had to the accompanying drawing, forming part thereof.

In the drawing—

Fig. 1 is a top plan view of a game board embodying the design of my invention;

Fig. 2 is an edge elevational view thereof.

I claim:

The ornamental design for a game board, substantially as shown.

ERICH J. P. STURM.
